UNITED STATES PATENT OFFICE.

GEORGE A. NEDROW, OF MONESSEN, PENNSYLVANIA.

HASP.

1,195,493.

Specification of Letters Patent. Patented Aug. 22, 1916.

Application filed February 8, 1916. Serial No. 77,035.

To all whom it may concern:

Be it known that I, GEORGE A. NEDROW, a citizen of the United States, residing at Monessen, in the county of Westmoreland and State of Pennsylvania, have invented 5 certain new and useful Improvements in Hasps, of which the following is a specification.

This invention relates to fasteners for 10 swinging or sliding doors, lids and the like and has special reference to a hasp which is adapted to receive the shackle of a padlock.

A further object of the invention is the provision of a hasp in which the padlock 15 may be freely turned to any desired position for conveniently inserting or extracting the shackle of the padlock.

A further object of this invention is the provision of a fastener which consists of 20 comparatively few parts and is simple in construction, but durable and well adapted to withstand the rough usage to which devices of this character are ordinarily subjected.

25 For a full description of the invention and the advantages and merits thereof, reference is to be had to the following description and the accompanying drawings wherein is illustrated the preferred form of my invention, in which,

Figure 1 is a side elevation showing the device attached to a door. Fig. 2 is a longitudinal section on the line 2—2 of Fig. 1.

The door A is adapted to close in the usual 35 manner against the casing or wall B, and the wall B has mounted thereon, one of the plates or leaves 1 of the hasp which is secured thereto by the fastening elements 2 which may consist of screws, bolts or any 40 other fastening means.

The plate 1 is provided with a bifurcation at its large end and the ends formed by said bifurcation are turned upon themselves to form knuckles 3 for the reception of a pivot 45 bolt 4 in a manner common to devices of this character.

Mounted upon the pivot bolt 4 in a manner similar to the mounting of the plate 1 is the plate 5 which is provided with an enlarged head 6, and extending from the head 6 is a tongue 7 which is adapted to be grasped by the fingers when the hasp is being placed in an inoperative position. The head 6 is provided with a circular opening 8 55 which receives a circular disk 9 adapted to freely revolve in the disk 8. Flanges 10 are

provided on the disk 9 and are designed to overlap the head 6 around the edge of the circular opening 8. It will be understood, of course that in assembling this disk and head, 60 one of the flanges is designed to be inserted through the opening 8 and afterward struck down to be permanently mounted upon the head 6 in a manner that is well known to the art. A longitudinal opening 11 is provided in the disk 9 for the purpose herein-after described.

Extending transversely through the door is an aperture 12 and on each side of the door is provided a countersunk circular recess 70 for the reception of washers 13. In order that the hasp may be secured to the door, I provide a staple member which consists in the stud 14 having threads formed upon one end for the reception of a nut 15 75 which threadedly engages with the threads of the member 14 and has a bearing upon one of the washers 13. Integrally formed with the opposite end of the stud 14 is a staple 16 which is provided with an opening 80 for the reception of a shackle for a padlock or other securing means.

When the device is mounted upon the door in the manner indicated and a padlock secured thereto by means of its shackle, it will 85 be seen that the padlock may be turned or positioned at any desired angle without danger of the staple being twisted from its fastening. The padlock may be easily removed from the staple without danger of 90 being cramped or fixed in an awkward position as is a common occurrence in the ordinary hasp.

From the foregoing it will be observed 95 that a very simple and durable hasp has been provided, the details of which embody the preferred form. I desire it to be understood however, that slight changes or modifications in the minor details of construction may be made without departing from the 100 spirit of the invention or the scope of the claims hereunto appended.

I claim:

1. A hasp comprising a hinged plate, a staple adapted to be rotatably mounted on a 105 door, and means rotatably mounted on said plate for receiving said staple.

2. A hasp comprising a plate, a head hingedly mounted upon said plate and provided with a circular aperture, a rotatable 110 disk mounted upon said head for rotation in the aperture of said head, means for secur-

ing said disk from displacement in said opening, and a rotatable staple adapted to be received by said disk.

3. A hasp comprising a plate mounted upon a door casing, a circular head hingedly mounted upon said plate and provided with an opening therein, a circular disk revolvably mounted in the opening in said circular head and provided with a longitudinal opening, flanges formed upon said disk and designed to overlap both faces of the circular plate, and a staple adapted to be inserted in said opening in said disk.

4. A hasp comprising a plate, a circular head hingedly mounted upon said plate and provided with a circular opening therein, a rotatably mounted disk provided with means adapted to overlie the edges of the opening in said head, and a staple rotatably mounted in the opening in the door and adapted to be received by an opening provided in said disk.

5. A hasp comprising a hinged plate

mounted upon a door casing, and provided with a central circular aperture, a rotatably mounted disk arranged in said aperture and provided with a peripheral groove for receiving the edge of said circular aperture, said disk being provided with a transversely extending elongated opening in its center, a staple rotatably mounted in an opening in the door, said staple comprising a stud provided with screw threads, a nut screw threadedly mounted upon said stud at the opposite side of said door, the end portion of said staple being enlarged to provide a shoulder for bearing against the side of the door and elongated whereby it may be extended through the elongated aperture in said disk.

In testimony whereof I affix my signature ⁴⁰ in presence of two witnesses.

GEORGE A. NEDROW.

Witnesses:

WILLIAM KNOX,
JACOB A. NEDROW.
